UNITED STATES PATENT OFFICE.

JOHN HENRY BALMER, OF MAPLEWOOD, NEW JERSEY, ASSIGNOR TO J. H. BALMER CO., OF NEWARK, NEW JERSEY, A CORPORATION OF NEW JERSEY.

SHELF-SUPPORTING BRACKET.

Application filed November 11, 1924. Serial No. 749,258.

To all whom it may concern:

Be it known that I, JOHN H. BALMER, a citizen of the United States of America, and resident of Maplewood, in the county of Essex and State of New Jersey, have invented a new and Improved Shelf-Supporting Bracket, of which the following is a full, clear, and exact description.

This invention has relation to supports and has particular reference to a shelf supporting bracket which is particularly designed for supporting glass shelves in bath rooms.

One of the principal objects of the present invention is to provide an improved shelf supporting bracket which functions to prevent longitudinal, lateral and accidental vertical displacement of a shelf when applied to the brackets.

As a further object the invention comprehends a bracket which affords means for rigidly supporting the shelf to avoid rocking of the same on its seat.

The invention furthermore contemplates a shelf supporting bracket which is comparatively simple in its construction, inexpensive to manufacture and install and which is highly efficient in its purpose.

With the above recited and other objects in view, the invention resides in the novel construction set forth in the following specification, particularly pointed out in the appended claim and illustrated in the accompanying drawings, it being understood that the right is reserved to embodiments other than those actually illustrated herein, to the full extent indicated by the general meaning of the terms in which the claim is expressed.

In the drawings—

Figure 1 is a perspective view illustrating a shelf supported by brackets constructed in accordance with the invention.

Fig. 2 is a plan view of one of the brackets.

Fig. 3 is a front view of the same.

Fig. 4 is an inner side view of one of the brackets.

Fig. 5 is a sectional view taken approximately on the line 5—5 of Fig. 4.

Referring to the drawings by characters of reference 10 designates the base of the bracket which is provided with an out-

wardly projecting arm 11 having a lateral flange 12 at the inner side of its lower edge. 55 The flange 12 is provided at its outer and inner ends with bearing steps 13 upon which the shelf S is adapted to rest so that the same is supported from two bearing points rather than throughout its entire upper surface. 60 At its forward extremity the flange 12 is provided with an abutment lug 14 between which and the inner face of the base the shelf is received to prevent forward or rearward displacement while the 65 ends of the shelf contact with and abut the arms 11 to prevent longitudinal shifting or displacement. Immediately above the inner corners of the shelf, the bracket at the juncture of the base 10 with the arm 11 70 is provided with an overhanging shoulder 15 which functions to prevent accidental upward displacement of the shelf from the brackets.

Under this arrangement the shelf S may 75 be applied to the brackets by inserting the rear corners under the shoulders 15 and then sliding the same rearwardly until the front edge is free of the abutment lug 14. To remove the same the operation is reversed 80 namely the front edge is raised until it clears the abutment lugs 14 after which the shelf is moved forwardly until the rear corners are clear of the shoulders 15.

I claim:

A shelf supporting bracket comprising a base, an arm projecting outwardly from said base, the base gradually merging into the arm where connected to said arm, a flange projecting inwardly from the lower 90 marginal edge of the arm and integrally joined to the base member at the inner end of said arm, the base member being cut away where the inner end of the flange joins the base member to provide a pocket 95 to receive an end of a shelf and a shoulder to prevent accidental upward displacement of the rear corner of said shelf from the bracket, bearing seats raised above the flange 100 at the opposite end of the flange to provide spaced points upon which the end of the shelf is seated, and a stop lug at the outer end of the arm and disposed above the flange.

JOHN HENRY BALMER.
